BUFFING-MACHINE.

No. 822,154.

Specification of Letters Patent.

Patented May 29, 1906.

Application filed January 4, 1904. Serial No. 187,662.

To all whom it may concern:

Be it known that I, ANDREW W. ROGERS, a citizen of the United States, residing at Beverly, in the county of Essex and Commonwealth of Massachusetts, have invented 5 certain Improvements in Buffing-Machines, of which the following description, in connection with the accompanying drawings, is a specification, like reference characters on the drawings indicating like parts in the several figures.

This invention relates to machines or devices for buffing and cleaning the bottoms of boots and shoes.

15 It is customary to buff the entire bottom of a shoe for removing the grain from the leather and forming a nap on its surface which gives the shoe-bottom a velvety appearance. The fore part of the shoe and the 20 tread of the heel are generally buffed on a cylindrical roll having a coarse sandpaper covering, which rapidly removes the grain and forms the nap on the leather. Owing to its shape, however, a roll cannot be used in 25 the angle formed by the shank and the breast of the heel. For this reason it is the practice to buff the rear part of the shank at a separate operation by means of an abrading device or pad secured to the end of a 30 rotary spindle, the pad being provided with an abrasive covering of sandpaper or emery-cloth, the working face of which is substantially perpendicular to its axis of rotation.

One important object of the present invention is to provide an improved abrading device which may be used for buffing both the fore part and the shank of shoe and which is especially adapted for buffing the rear part 35 of the shank in the angle made by the shank and the breast of the heel.

To this end one feature of the present invention consists in providing a holder and an abrading device comprising a plurality of pieces of abrasive material of different sizes 40 and arranged in layers with the smaller pieces superposed on the larger ones. Such an abrading device will present a thin edge at all times which adapts the device for use in buffing the shank of a shoe in the angle 45 formed with the breast of the heel without the edges of those layers above the acting one coming into contact with the breast of the heel and scratching it or becoming worn or frayed. Preferably, also, the layers of the

abrading device will be connected together 55 near their centers in such manner as to be restrained from relative radial or rotative movement as a whole while being free and unconnected except near their centers. This permits the edge portion of the abrading device to bend easily and adapt itself to the conformation of the surface of the work which is pressed against it. This device can be continuously used without any stopping of the machine while successive layers 60 are being worn out, when the entire abrading device will be removed and a new one substituted. This saves the waste of time occasioned by the old practice of using a single abrasive covering, which soon wore away and 65 had to be renewed, necessitating the stopping of the machine and loss of the workman's time, not only while he was removing a worn-out covering and putting on a new one, but also while he was waiting for the 70 machine to stop before he could remoye the old covering and while he was waiting for the 75 machine to get up speed after the new covering had been applied.

Other features of the invention, including 80 certain details of construction and combinations of parts, will be explained in the following description and pointed out in the claims.

In the drawings, Figure 1 is a side elevation of a buffing-machine embodying the 85 present invention. Fig. 2 is a central vertical section of the upper portion of the machine on the dotted line 2 2 of Fig. 3. Fig. 3 is a front view of the upper portion of the machine. Fig. 4 is a vertical section on the dotted line 4 4 of Fig. 3. Fig. 5 is a perspective view of the holder provided with a pad or support for the improved abrading device. Fig. 6 is an edge view, on a larger scale and partly in section, of a preferred form of the 90 improved abrading device of the present invention. Fig. 7 is a sectional view showing a modified form of means for securing the abrading device in working position. Fig. 8 is a perspective view of a modified form of 95 abrading device. Fig. 9 is a view illustrating the operation of the improved abrading device in buffing the portion of the shank 100 next to the breast of the heel.

The machine comprises a standard 1, resting on the floor and having at its rear side posts to support the bearings 2 of a driving-shaft 4, provided with pulleys by which

the several parts of the machine are operated. The driving-shaft is provided also with fast and loose pulleys to receive a belt (not shown) by means of which the shaft is driven from a suitable source of power.

The pulley 6 receives a belt 12, which after passing over idlers 14 (one only of which is shown in Fig. 1) extends around a pulley 16 on a spindle 20. The spindle 20 is supported in a bracket 22, having a stem 24 projecting from its rear side and adjustably clamped in position in the machine-frame by a bolt 26. The bracket 22 is provided with arms, to which are secured, by means of cap-plates 36 38, the sleeves 32 and 34, which constitute bearings for the spindle 20. The sleeves have convex portions by means of which they are held from longitudinal movement in the bracket, as shown in Fig. 2. The pulley 16 for the spindle is formed as a part of a sleeve which surrounds the spindle and is secured to it and by abutting against the sleeves 32 and 34 prevents longitudinal movement of the spindle in said sleeves. The spindle is also provided with a second pulley located below the pulley 16 and, as shown, formed upon the same sleeve as the pulley 16.

The spindle 20 is provided near its lower end with a flange 40, which engages a flange 42 of a clamping-nut 44. The clamping-nut 44 is adapted to screw upon the upper end of a threaded sleeve 46, provided at its lower end with a flange 48 to receive the upper wall of a hollow flexible pad 50. The sleeve is provided with a longitudinal slot 52 to receive a stud 54, projecting laterally from the spindle 20, whereby the sleeve is compelled to rotate with the spindle, all as shown in Fig. 2. A washer or clamping-plate 56 is loosely supported upon the sleeve 46 and is arranged to bear upon the folded-over edge or attaching portion of an abrasive covering 58, so as to clamp said covering and the upper wall of the hollow pad against the flange 48. The clamping-plate is forced down to secure the pad and abrasive covering in position by a nut 60, working upon the screw-threaded sleeve. By this means the hollow flexible pad is secured to the sleeve in a manner to prevent the escape of the air with which the pad is kept filled. The air is maintained under suitable pressure for distending the pad and yieldingly supporting the abrasive covering which constitutes the working face of the pad. This provides a device having a yielding working surface which will adapt itself perfectly to the shape of the different parts of the shoe-bottom presented to it.

For supplying the hollow pad with air under pressure the spindle 20 is provided with an air-passage 62, which communicates through an air-passage in the bracket 22 with a chamber 70. The bracket is provided at the upper end of the spindle 20 with a stuffing-box, 65 which comprises a packing 64, held in place

by a clamp 66 and screws 68. Air is forced into the chamber 70 by a pump contained in a cylinder 72. The pump may be of any usual or suitable construction and is operated through a pitman 76, connected with a crank 78 on a shaft 80. The shaft 80 is provided with a pulley 82, which is connected by a belt 84 with a pulley (not shown) on the main driving-shaft 4. The air-chamber 70 is provided with a safety-valve, the cap 86 of which may be adjusted to regulate the pressure of the air in the chamber and in the pad.

The pulley 94 on the spindle 20 is connected by a belt 96 with a pulley 98, fast on a second spindle 100. The spindle 100 is supported by a bracket 102, which is secured to the machine-head and provided with arms in which are mounted sleeves 108 110, constituting bearings for the spindle. The spindle has a flange 112, which is engaged by a flange 116 in a threaded clamping-nut 114, adapted to screw upon the upper end of a threaded sleeve 120. The sleeve 120 is provided at its lower end with a wide flange 128 and has a longitudinal slot 122 to receive a stud 124 on the spindle 100, whereby it is compelled to rotate with the spindle. The sleeve and flange constitute a holder adapted to receive any suitable form of work member, but preferably will be provided with a pad or disk 132, of leather or other suitable flexible or yielding material, for supporting the improved abrading device hereinafter described. The pad or support may be secured to the flange of the holder by screws 133, as shown in Fig. 5.

The spindle 100 is provided with a loose pulley 140, adjacent to the fast pulley 98, above mentioned. The loose pulley preferably is smaller than the fast pulley, and the flange 142 on that side of the fast pulley adjacent to the loose one is reduced in size, so as to permit the belt to be shifted easily by the workman over upon the loose pulley by merely pressing down on the belt with his finger or with some tool kept for the purpose. The return of the belt to the fast pulley is facilitated by the low flange of the fast pulley and also by the smaller size of the loose pulley, whereby the belt is caused to hug the fast pulley as it is moved over upon it. This arrangement for disconnecting the belt from the spindle 100 permits the said spindle to be easily and quickly stopped independently of the other mechanisms of the machine.

The provision of means whereby the spindle 100 may be disconnected from the spindle 20 is of material advantage because the spindle 20 can be stopped only by stopping the driving-shaft and all parts of the machine operated by it, and as these moving parts have a considerable momentum it takes some time for them to come to rest. The spindle 100, however, is light and quickly comes to rest 130

when the belt 96 is shifted over upon the loose pulley. It saves the workman much time to be able to disconnect the spindle 100 from its driver and so stop it quickly for removing a worn-out abrading device and applying a new one instead of having to disconnect the whole machine from its driving means and wait for the machine to come to rest.

In the preferred embodiment of the invention the abrading device used on the spindle 100, in connection with the pad or support 132, above described, comprises a plurality of substantially circular pieces or disks 151 of sheet material, each having an abrasive surface on one side. The disks are arranged concentrically in layers with the sides having the abrasive surface lowermost and are secured to the holder by a pin or bolt 152, passing centrally through the device and held in place in any suitable manner—such, for instance, as by extending through the holder and spindle—and having screw-threaded engagement with a nut 153, as shown. An abrading device of this construction can be used continuously while the several layers are being used, for as soon as one layer is worn through the fresh abrasive surface of the next layer is exposed to use, and this continues until the last layer has been used.

Preferably the pieces of which the abrading device is built up will be of varying sizes and will be arranged with each of the smaller pieces on top of a larger one, so that it comprises a plurality of superposed layers of diminishing diameter. This provides an abrading device having a thin edge or periphery adapted to enter and thoroughly buff out the angle formed by the breast of the heel and the rear end of the shank. This construction also has the advantage that when the work is pressed against the face of the abrading device and bends it slightly, as shown in Fig. 9, the layers above the lowermost or acting one will not project beyond the periphery of the acting layer and scratch the breast of the heel or become frayed.

Preferably and as herein shown the abrading device will be provided with a backing of non-abrasive material, such as the pasteboard disk 157. This backing forms a support for the last layer of abrasive material while it is being used and protects the pad or support 132 from injury in case the abrading device is used after the last layer is worn through. The support 132 may be omitted, if desired, and the pasteboard packing alone used.

The support 132 when used must be flexible enough to permit the pad to be bent by pressure of the work against it, and preferably it will be slightly smaller than the smallest of the layers of the abrading device, so as to support the device to within a short distance of its edge when the last layers are being used.

Preferably, although not necessarily, the abrading device will be formed with the marginal portion slightly upturned or convexed, as shown, so that when the work is first presented to a new abrading device the edge will not tend to form scratches, as sometimes occurs if the work is carelessly presented to a perfectly flat abrading device. The abrading device may be shaped conveniently by molding it after the several disks have been assembled and, if desired, may be made convex throughout.

It is desirable, although not essential, to provide auxiliary means, in addition to the bolt 152, for securing the abrading device in position and for supporting the pieces of abrading material as near to their peripheries as is practicable. The flange 128 of the holder and the support 132 are provided, therefore, with alined holes 160, (see Fig. 5,) preferably located at diametrically opposite points, and the abrading device is provided with holes 162 so located that they may be positioned in alinement with the holes 160. The pin or bolt 152 is provided with one or more arms 164, the arms having upturned prongs 166 for entering the holes in the abrading device, support, and holder. These arms and prongs engage the abrading device at either side of the center thereof and insure against any relative rotative movement taking place between said parts and also add very much to the effectiveness of the abrading device by affording for the layers of material a support which is located between the center and the periphery of the device. This arrangement is very advantageous because each piece of abrasive material is supported near the portion which receives the wear, and thereby is prevented from twisting and turning and is held up to the work much better than it would be if it were supported at its center only and also because each piece of abrasive material affords support to those above and below it. In addition to the tendency of the roughened surface of one layer to grip or sink into the smooth surface of the layer next below it there is a further important advantage arising from the fact that my improved device is preferably continuously used until all the pieces of abrasive material are worn out, and consequently the central portions which are held by the prongs 156 remain after they have been worn out in position to support the upper layers. In Fig. 7 is illustrated a modified form of means for securing the abrading device in place which also affords the advantages just referred to.

In this construction the lower end of the spindle 100 has a screw-threaded aperture to receive a screw-bolt which passes through a plate or washer 155. The plate 155 is provided with arms 156 to extend through the holes in the abrading device, the support, and the holder. The abrading device preferably

will be provided during the course of its manufacture with means, such as an eyelet 159 in the central opening, for securing the several disk or layers in assembled position. 5 The layers might, however, be secured by eyelets in the holes 162, as shown in Fig. 8, if desired, or they might be connected by any other suitable means. It will be understood, however, that the peripheries of the several 10 layers are entirely disconnected from one another, so that their marginal portions are free to move on one another when the abrading device is bent by pressure of the work against it, as shown in Fig. 9.

15 The standard 1 is provided on the right-hand side with bearings for a shaft 170, which carries a rotary brush 172, to which the workman may present the shoe for removing any dust that may have accumulated on it. The 20 shaft 170 is rotated by a pulley 174, which receives a belt 176, extending from a shaft 180, also mounted in bearings in the standard 1. The standard is formed with an open space to receive a fan 182, mounted on the shaft 180. 25 The standard also supports the forwardly-projecting flues 184, extending from the fan-chamber and the open ends of which are located adjacent to the buffing and cleaning devices. Another flue 186 partially incloses 30 the brush 172. The shaft 180 is rotated by a belt 188 from a pulley 10 on the driving-shaft in a direction to cause the fan to suck the dust from the several work members in through the flues and to force it out through 35 an exhaust-opening 190, which communicates with a dust-collector or with the open air.

In the use of the machine the workman will hold a shoe in his hands and present it first to the abrading device 150 on the spindle 40 100 for buffing the shank, or it may be the whole bottom of the shoe. He then will present the shoe to the cleaning-pad 50, which removes all scratches or marks and rubs up the nap to produce a velvety surface on the 45 leather. The workman will present the shoe next to the brush 172 for removing the dust from the sides and bottom of the shoe. This is all done with one handling of the shoe, and the buffing and cleaning members and the 50 brush are so arranged that the workman may present the shoe to each of these work members in succession without being obliged to walk from one part of the machine to another. When the abrading device becomes 55 unfit for further use, the workman may shift the belt 96 from the fast pulley 98 to the loose pulley 140 by pressing down on the belt with a light touch of his finger or with any 60 convenient instrument. The lower flange 142 on the fast pulley facilitates the shifting of the belt and the spindle comes to rest immediately after the belt is shifted from the fast pulley. The workman will then remove the worn-out abrading device and replace it 65 with a fresh one. The belt 96 may then be

shifted to the fast pulley and the machine is again ready for use. The shifting of the belt from the loose to the fast pulley is very easily accomplished by reason of the fast pulley being somewhat larger than the loose pulley, so that the moving belt is caused to hug the fast pulley as it is moved over upon the low rim at the lower side of said pulley. 70

If desired, the spindle 100 may be stopped whenever a layer of abrasive material becomes worn and that layer torn off to expose the fresh abrasive surface of the next layer. Preferably, however, the abrasive device will be used continuously, while the successive layers of abrasive material are being worn out, each layer at it wears through uncovering for use the fresh surface of the next layer above it. This will be done without stopping the spindle until all the layers of abrasive material have been worn away and the 80 device is unfit for further use. 85

By the term "abrading device" as herein employed I mean to include a device of the character described adapted for buffing, cleaning, or polishing, or any similar work. 90

Having described my invention, what I claim as new, and desire to secure by Letters Patent of the United States, is—

1. The combination with a holder formed with a plurality of holes, of an abrading device comprising a plurality of pieces of abrasive material arranged in layers and having corresponding holes, and means extending through the holes for securing the device in position on the holder. 95

2. The combination with a holder and an abrading device comprising a plurality of pieces of abrasive material arranged in layers, of means for securing said device to the holder, and additional securing means for entering the abrasive material. 105

3. The combination with a support of non-abrasive material, of an abrading device comprising a plurality of pieces of abrasive material of varying diameters arranged in layers with the smallest layer next to the support, said support being of a diameter slightly less than the said smallest layer whereby to support said layer from its center to within a short distance of its edge. 110

4. The combination with a holder and an abrading device, of a securing device comprising a stem extending centrally through the abrading device and into the holder and provided with arms having prongs to engage the abrading device and holder at two or more points to prevent relative rotative movement of said parts. 120

5. The combination with a rotary holder and an abrading device, of a securing device comprising a stem extending through the abrading device and provided with an arm arranged to engage said device eccentrically, and means for securing the stem in position in the holder. 125

6. A device of the class described comprising a plurality of pieces of material, each having an abrasive surface, said pieces being of circular form and of varying diameters and being placed in layers with their abrasive surfaces on the same side.
7. In a machine of the class described, the combination of an abrading device comprising a plurality of circular layers of abrasive material of diameters varying from the largest in the outer layer to the smallest in the inner layer, with means for supporting and actuating said device, the combination being arranged to permit continuous use of said abrading device while successive layers of the abrasive material are being worn out.
8. As a new article of manufacture, an abrading device comprising a plurality of pieces of material, each having an abrasive surface, said pieces being of circular form and being placed in layers with their abrasive surfaces on the same side, and also being secured together.
9. As a new article of manufacture, an abrading device comprising a plurality of pieces of material, each having an abrasive surface, said pieces being of circular form and being arranged in concentric layers with their abrasive surfaces all on the same side, said device having provision for securing the pieces together at two or more points to prevent relative rotative movement thereof.
10. As a new article of manufacture, an abrading device comprising a plurality of circular pieces of abrasive material, said pieces being of varying diameters and being placed in concentric layers, and also being secured together at two or more points.
11. As a new article of manufacture, an abrading device comprising a plurality of layers of flexible abrasive material secured together, the marginal portions of said layers of material being free to move relatively.
12. A device of the class described, comprising a plurality of superposed pieces of abrasive material arranged in layers of diminishing size with their abrasive surfaces on the same side.
13. An abrading device comprising a plurality of superposed layers of flexible abrasive material, the marginal portions of the layers of material being disconnected to permit said portions to move relatively, said superposed layers being of diminishing size whereby the upper layers will not project beyond the periphery of the lowest one when the device is bent upwardly.
14. As a new article of manufacture, an abrading device comprising a plurality of pieces of abrasive material of circular form and of varying diameters, said device presenting a convex abrasive surface near its edge.
15. As a new article of manufacture, an abrading device comprising a plurality of pieces of abrasive material of circular form and of varying diameters and a backing of non-abrasive material secured thereto.
16. As a new article of manufacture, an abrading device comprising a plurality of circular pieces of abrasive material arranged in concentric layers and secured together at a plurality of points.
- In testimony whereof I have signed my name to this specification in the presence of two subscribing witnesses.
